ROAD TORCH

Henry J. Sauer, Fairfield, Conn., assignor to The Kilborn-Sauer Company, Fairfield, Conn., a corporation of Connecticut

Application July 13, 1934, Serial No. 734,889

5 Claims. (Cl. 67—55)

The present invention relates to road torches, particularly of the type used for illuminating road obstructions. These torches must be of sturdy construction, as they are usually laid directly on the road surface and are handled roughly, and must be such as to insure a large bright, and steady flame under all weather conditions. It is furthermore desirable that the wick may be conveniently adjusted and cleaned in order to keep the torch at its highest efficiency at all times. It is an object of the present invention to provide a torch which meets these requirements, and I particularly propose to provide a burner construction in which the wick is at all times baffled in all directions against wind and rain, and which at the same time allows adequate combustion air to enter, and which also provides relatively large outlets for the flame. It is further proposed to provide means by which the flame will be mushroomed so that it will be relatively wide and therefore provide a greater illumination and visibility, and also to provide means for preventing the trapping of gases in the upper portion of the burner. A further object is to provide a burner in which all parts are permanently attached. Another object is to provide a closure for the burner which may be used for snuffing out the flame, and also to provide handle means for hanging up the torch when not in use, and which is arranged to tightly retain the cover and burner against looseness.

With the above and other objects in view, an embodiment of the invention is shown in the accompanying drawing and this embodiment will be hereinafter more fully described with reference thereto and the invention will be finally pointed out in the claims.

In the drawing:

Fig. 1 is a side elevation, with parts broken away, showing the torch according to the exemplary illustrated embodiment of the invention, the cover being shown in place.

Fig. 2 is a top plan view, with parts broken away.

Fig. 3 is a horizontal sectional view, taken along the line 3—3 of Fig. 1, the cover being removed.

Fig. 4 is a vertical sectional view taken along the line 4—4 of Fig. 3.

Fig. 5 is a bottom plan view of the burner and the contiguous under side of the top of the fuel receptacle.

Fig. 6 is a perspective view of the burner, removed from the receptacle.

Similar reference characters indicate corresponding parts throughout the several figures of the drawing.

Referring to the drawing, the torch, according to my invention, comprises a fuel receptacle adapted to contain oil and consisting of a cup

shaped base portion 10, flanged outwardly and downwardly at its upper edge 11, and a dome shaped top portion 12 seated upon the flange 11 and secured thereto by curling its edge about the flange 11, as at 13. The upper portion of the top 5 12 is flat and is provided with a circular opening having inwardly bent segmental cam flanges 14 and 15 bent downwardly from its edge, the ends of these flanges being spaced apart by cut-outs 16 and 17. The cam flanges 14 and 15 are of increasing height from one end to the other, the 10 low end of one flange being adjacent the high end of the other, and are adapted to removably secure the burner element to the receptacle, as will hereinafter more fully appear.

The burner element comprises a lower shell member consisting of a reduced diameter lower end portion 18 having its lower end flanged inwardly as at 19, an outwardly stepped intermediate portion 20 of greater diameter than the 20 lower portion 19, and an outwardly stepped upper portion 21 of greater diameter than the intermediate portion 20. A tubular wick holder 22 has its lower end secured to the flange 19 by means of a bead 23, formed upon the wick holder near its lower end and which engages the upper side of the flange 19, and by curling over the lower edge of the wick holder upon the under surface of the flange 19, as at 24. At diametrically opposed points the flange 19 is indented 25 and the metal is pressed outwardly to provide a pair of lugs 25 and 26 adapted to cooperate with the cam flanges 14 and 15 to retain the burner in place, as will presently more fully appear.

The burner further comprises a guard 27 having its lower portion outwardly offset, as at 28, and secured to the upper portion 21 of the lower member of the burner by curling over the lower edge of the portion 28, as at 29. The side wall of the guard is lanced along a pair of vertically spaced circumferential lines, the lancing being in the form of three slots or shearing cuts 30 of equal length having their ends spaced a short distance apart. The portions of the metal of the side wall of the guard between these lancing 35 is pressed inwardly to provide three V-shaped 40 inwardly extending walls 31, the apices of the 45 walls being projected slightly within the interior diameter of the wick holder 22.

The wick holder 22 has its upper end downwardly spaced from the edges of the wall portion 31, and the wick 34, as it is engaged in the wick holder, is pressed upwardly beyond the upper end of the wick holder into engagement with the inwardly projected edges of the walls 31.

In the intermediate portion 20 of the lower member of the burner there are preferably provided a series of small holes 35. While these normally admit a small amount of air their primary purpose is to provide an outlet for the accumu- 60

lation of water that may find its way into the burner, the holes permitting the water to run off as it collects and thus prevent any possibility of the water reaching the exposed upper end of the wick, particularly in the event that the torch becomes extinguished through burning out of the oil during a rain.

The burner is engaged in the receptacle by inserting the lower end portion 18 in the opening of the receptacle with the lugs 25 and 26 first engaged through the cut-outs 16 and 17. Thereupon the burner is turned to bring the lugs into wedging engagement with the cam surfaces of the flange 14 and 15 and thereby tightly secure the burner in place. A washer 36 of fibre or other suitable material is preferably interposed between the stepped portion 20 and the upper flat surface of the receptacle.

A cap 37 is adapted to be engaged over the burner when it is not in use, and may be employed for the purpose of snuffing out the flame. A wire handle 38 is hingedly secured at its lower ends to the top 12 of the receptacle by means of brackets 39 and 40, and at its upper portion is provided with a loop 41, so that the torch may be easily carried thereby, or the loop may be employed for hanging it upon a suitable support. The wire handle is slightly springy and its upper portion is adapted to tightly engage the upper surface of the cap 37 to secure it in place, and for this purpose the cap is provided at each side of its top with pairs of pressed out bosses 42 between which the handle is seated, being swung into and out of place by being forced over these bosses.

The operation is as follows:—

In preparing the torch for use the wick is forced up into the tubular wick holder 22 against the inwardly projected edge portions of the wall portions 31, these edge portions thereby limiting the projection of the wick. After the wick has become burned or charred it may be trimmed and cleaned at its projecting end by turning it so that the edges of the wall portions 31 scrape off the burned or charred portion of the wick. In this way the wick may be conveniently cleaned and kept in efficient working order at all times. When lighted the flame will mushroom at the top and emerge over the upper edges of the wall portions 31 thereby producing a very wide luminous flare. A portion of the flame will also pass beneath the lower edges of the walls 31. At the same time some portion of the flame will be through the slot 33 and as this portion will be relatively wide and thin it will provide a greater illumination in the direction facing the wide dimension of this flame. In this way the brilliance of the flare is directionally increased, and at the same time the slot provides an outlet for gasses which might otherwise accumulate in the top portion of the guard. Combustion air will enter beneath the lower edges of the wall portions 31, being baffled as it enters through striking the surfaces of these wall portions, so that in the case of a high wind the force of the air will be reduced before it comes into contact with the flame. The wick holder 22, it will be noted, is permanently secured to the lower portion of the burner, and through this lower portion to the guard, and is thus heated through conduction, so that the upper end of the wick is heated and the oil carried thereby maintained at its proper flash point.

I have illustrated and described a preferred and satisfactory embodiment of the invention, but it will be obvious that changes may be made therein within the spirit and scope thereof, as defined in the appended claims.

Having thus described my invention, what I claim and desire to secure by Letters Patent is:—

1. A burner for a road torch or the like, adapted to be secured to a fuel receptacle, comprising a tubular wick holder, a guard surrounding said wick holder having a side wall and a top wall, said side wall having inwardly pressed portions, the upper and lower edges of which are severed from said side wall and whereby passages between the interior and exterior of said guard are provided about the upper and lower edges of said inwardly pressed portions. 10

2. A burner for a road torch or the like, adapted to be secured to a fuel receptacle, comprising a tubular wick holder, a guard surrounding said wick holder having a side wall and a top wall, said side wall having a plurality of circumferentially spaced inwardly pressed portions, the upper and lower edges of which are severed from said side wall and whereby passages between the interior and exterior of said guard are provided about the upper and lower edges of said inwardly pressed portions. 20

3. A burner for a road torch or the like, adapted to be secured to a fuel receptacle, comprising a tubular wick holder, a guard surrounding said wick holder having a side wall and a top wall, said side wall having a plurality of circumferentially spaced inwardly pressed portions, the upper and lower edges of which are severed from said side wall and whereby passages between the interior and exterior of said guard are provided about the upper and lower edges of said inwardly pressed portions projecting inwardly beyond the inner periphery of said wick holder. 30

4. A burner for a road torch or the like, adapted to be secured to a fuel receptacle, comprising a tubular wick holder, a guard surrounding said wick holder having a side wall and a top wall, said side wall having a plurality of circumferentially spaced inwardly pressed portions, the upper and lower edges of which are severed from said side wall and whereby passages between the interior and exterior of said guard are provided about the upper and lower edges of said inwardly pressed portions projecting inwardly beyond the inner periphery of said wick holder, and the upper end of said wick holder being spaced below said inwardly pressed portions. 40

5. A burner for a road torch or the like, adapted to be secured to a fuel receptacle, comprising a tubular wick holder, a guard surrounding said wick holder having a cylindrical side wall and a top wall, said side wall having a plurality of circumferentially spaced inwardly pressed portions, the upper and lower edges of which are severed from said side wall and whereby passages between the interior and exterior of said guard are provided about the upper and lower edges of said inwardly pressed portions, said top wall having a slot therein. 60
